US0D1109700S

(12) **United States Design Patent** (10) Patent No.: **US D1,109,700 S**
(45) Date of Patent: ** Jan. 20, 2026

(54) **BATTERY PACK MOUNTING DEVICE**

(71) Applicant: **Positec Power Tools (Suzhou) Co., Ltd.**, Suzhou (CN)

(72) Inventors: **Wang Huo**, Suzhou (CN); **Fanqing Ding**, Suzhou (CN)

(73) Assignee: **Positec Power Tools (Suzhou) Co., LTD.**, Suzhou (CN)

(**) Term: **15 Years**

(21) Appl. No.: **35/518,844**

(22) Filed: **Oct. 28, 2022**

(80) **Hague Agreement Data**

Int. Filing Date: **Oct. 28, 2022**

Int. Reg. No.: **DM/224921**

Int. Reg. Date: **Oct. 28, 2022**

(57) **CLAIM**

The ornamental design for a battery pack mounting device, as shown and described.

DESCRIPTION

1.1 is a front perspective view of a battery pack mounting device showing the new design;

1.2 is a front view thereof;

1.3 is a back view thereof;

1.4 is a left-side view thereof;

1.5 is a right-side view thereof;

1.6 is a top view thereof; and

1.7 is a bottom view thereof.

The broken lines depict portions of the battery pack mounting device that form no part of the claimed design.

1 Claim, 7 Drawing Sheets
